UNITED STATES PATENT OFFICE.

JOHN H. DAVENPORT, OF GRAND ISLAND, NEBRASKA.

BOILER-FLUE.

No. 856,516.

Specification of Letters Patent.

Patented June 11, 1907.

Application filed August 20, 1906. Serial No. 331,338.

To all whom it may concern:

Be it known that I, JOHN H. DAVENPORT, a citizen of the United States, residing at Grand Island, in the county of Hall and State of Nebraska, have invented a new and useful Boiler-Flue, of which the following is a specification.

This invention relates to boiler flues and to the method of securing them to the flue sheets.

The object of the invention is to provide a sectional flue one section of which is formed of an integral part of the rear flue sheet and in addition thereto is retained by the usual bead. The adjoining ends of the sections of the flue are threaded so as to be easily secured together without danger of leaking.

With the above and other objects in view the invention consists of certain novel features of construction and combinations of parts which will be hereinafter more fully described and pointed out in the claims.

In the accompanying drawings is shown the preferred form of the invention.

In said drawings: Figure 1 is a section through a boiler and showing the flues in position therein; Fig. 2 is an enlarged section showing the connections between the flues and flue sheets; and Fig. 3 is a section showing a step in the process of welding the flue stubs to the back flue sheet.

Referring to the figures by characters of reference, 1 is the back flue sheet of a boiler from which extend short flue stubs 2 of different lengths. The front flue sheet 3 of the boiler has long flue sections 4 secured thereto and disposed in alignment with and secured to the stubs 2. Said stubs are brazed within the rear flue sheet and beaded as shown at 5 and the main flue sections 4 are rolled and beaded at their outer end as shown at 6 so as to be held in place in the usual manner. The adjoining ends of the stubs 2 and flues 4 are screw threaded externally as at 7 and project into and engage a sleeve 8 which serves to hold them together without leaking.

When it is desired to construct a boiler with flues of the character described, a suitable furnace is prepared ready to receive the rear flue sheet. The flue stubs are then threaded at their inner end portions and inserted into the flue openings in the rear flue sheet and then rolled and expanded to form beads 5 of the usual form. After all of the stubs have been placed in proper position within the flue sheet said sheet is placed in a

horizontal position with a bank 9 of fire clay around the outer edge thereof. Spelter 10 is then poured around each flue so as to fill the crevices and a portion of the spelter will also spread over the inner surface of the flue sheet. After the spelter has been distributed in this manner the entire flue sheet with the stubs therein is placed within a furnace and the spelter thoroughly melted. The flue sheet can then be removed and the stubs will be found to be securely brazed in position. Said flue sheet can then be lifted in place upon the boiler. The main flue sections 4 are then inserted through the front flue sheet 70 and, beginning at the bottom of the boiler, said sections 4 are coupled to the corresponding stubs 2 by means of the sleeves 8 which serve to hold the flue sections securely together. As the stubs are of different lengths 75 the coupling sleeves 8 will not interfere with said flues being placed close together and the circulation of water around the flues adjacent the couplings will not be interfered with. After the flue sections 4 have all been secured the outer ends thereof are rolled and expanded to form the beads 6.

By assembling the parts of a furnace in the manner herein described the flues are rendered practically indestructible as far as the effect of the heat thereon is concerned because the stubs are formed practically integral with the rear flue sheet and leakage is therefore absolutely prevented. Moreover, the brazed connection between the stubs and 90 flue sheet is reinforced by the beads 5 and should the brazing of any one of the stubs be defective the bead of said stub would be as efficient in preventing leakage as the beads ordinarily used for that purpose. The 95 joints between the flue sections are disposed entirely within the boiler and will not therefore be affected by the heat because entirely surrounded by the water within the boiler. The spelter thoroughly seals the rear end of 100 the boiler and as it covers the inner surface of the rear flue sheet it serves to prevent said sheet from corroding. It will of course be understood that instead of screwing the ends of the flue sections into a sleeve said sections can screw one into the other or various other threaded connections can be utilized.

The preferred form of the invention has been set forth in the foregoing description; but I do not limit myself thereto, as I am aware that modifications may be made therein without departing from the spirit or sacri-

ficing the advantages thereof, and I therefore reserve the right to make such changes as fairly fall within the scope of the claims.

What is claimed is:

- 5 A boiler comprising front and rear flue sheets, stubs extending through the rear flue sheet, the outer ends of said stubs having beads thereon overlapping the walls of the openings in the flue sheet, a layer of non-corrodible metal disposed upon and covering the inner face of the rear flue sheet and surrounding the stubs and constituting a solder, main
- 10

flue sections within the front flue sheet, and means between and spaced from the flue sheets for coupling together the inner face of the main flue sections and the stubs.

In testimony that I claim the foregoing as my own, I have hereto affixed my signature in the presence of two witnesses.

JOHN H. DAVENPORT.
